UNITED STATES PATENT OFFICE.

LOUIS JENSEN, OF CHICAGO, ILLINOIS, ASSIGNOR TO UNITED AUTOGRAPHIC REGISTER COMPANY, OF CHICAGO, ILLINOIS, A CORPORATION OF ILLINOIS.

STRIP-FEEDING MECHANISM.

Application filed April 30, 1924. Serial No. 709,954.

My present invention relates to an apparatus for feeding a strip or strips of material, and particularly structures that are actuated to feed the paper strips through an autographic register by means of a small electric motor or the like. Primarily, however, my present invention is for the purpose of feeding strips of material, whether paper, fabric, motion picture film, or the like, as its principles are well adapted for any of these types of mechanism.

One of the numerous objects of my invention is to provide motor-actuated means that will feed the strip or strips of material a predetermined distance and then stop so that further longitudinal movement of the strip will be discontinued until the apparatus is again set and started. In this connection I have provided a simple and effective switch operating device or cut-out structure that may be manually actuated for the purpose of disconnecting or breaking the circuit leading to the motor and permits the strip feeding mechanism to be actuated manually whenever it is so desired. In conjunction within the motor-driven mechanism there is provided means that will feed the strip or strips longitudinally, which will automatically discontinue the feed at predetermined locations on the strip, whether the motor-actuated mechanism is stopped or not.

In an autographic register, the strips, like the strips of cinematograph film, are previously perforated to determine the lengths of the respective tickets or spaces on the strip and the tickets or spaces may vary in length according to the service for which they are intended. The automatic means for stopping the feed coacts with the perforations in the strip or strips at the predetermined locations so that but a single predetermined length will be fed during each operation; but it is desirable to have the motor continue to operate for a period that would be sufficient to feed the longest ticket or predetermined length of the strip that it is desired to feed through the machine. I have accomplished this in a very effective and dependable manner by means of simple mechanism that will not readily get out of order and which is extremely compact so that it may be readily mounted upon the side wall of the register or other

strip feeding apparatus in connection with which it may be utilized.

I prefer to carry out my invention in substantially the manner hereinafter described, and as more particularly pointed out in the claims, reference being had to the accompanying drawings that form a portion of this specification, in which

Figure 1 is a vertical side elevation of an end portion of a strip feeding apparatus showing the application of my improvements thereto.

Figure 2 is a vertical transverse section thereof taken on line 2—2 of Figure 1.

Figure 3 is a top plan of the structure shown in Figure 1.

Figure 4 is a detail view, similar to Figure 1, but having the motor and worm wheel removed for the purpose of clearness.

Figure 5 is a view similar to Figure 4 showing the parts in a different position or when the structure has been set and is ready to begin operation.

Figure 6, is a fragmentary view, drawn to an enlarged scale, showing schematically two positions of a portion of the strip starting mechanism.

Figure 7 is an enlarged detail view of a fragmentary portion of the motor cut out showing the switch opened in a position to stop the motor.

Figure 8 is a view similar to Figure 7 showing the switch closed and the mechanism ready to start operation.

Figure 9 is a perspective view of a fragmentary portion of the structure showing means for holding the switch open while the device is operated manually.

Referring to the drawings, it will be seen I have employed an autographic register to illustrate a typical embodiment of my invention which autographic register comprises side walls 10 that are mounted upon the longitudinal edges of the base 11, and a platen 12 connects the upper edges of said walls. The strip feeding mechanism is such that the paper strip or strips are fed a predetermined distance and then the feeding mechanism becomes ineffective to move the strip or strips further. This mechanism is similar to that forming the subject matter of the copending application of Walter R. Barker and myself for Letters

Patent of the United States, which was filed February 9, 1922, Serial No. 535,293. The mechanism just alluded to feeds the desired lengths of the strips out at the delivery end of the structure, the strips being previously perforated at the end of each predetermined space or ticket and each ticket bears the desired printed notation thereon. The feed mechanism will now be briefly described in connection with Figure 2 of the drawings, where it will be seen that the same comprises a rotatable main shaft 13 (hollow) upon which is rigidly secured the grooved rollers 14 and 15 for co-operation with a knurled feed roller 16 that is mounted above the same and is provided with annular grooves 17 in registry with grooves in the rollers 14 and 15. A removable crank 18 is secured on the outer extended end of shaft 13 whereby the structure may be manually operated. The roller 16 carries a gear 19 on one end that meshes with a gear 20 fast upon the shaft 13, and after a complete operation of the feeding mechanism, the strips come to rest with a pair of perforations therein positioned in registry with rollers 14 and 15 between said rollers and the feed roller 16 so that further rotation of the main shaft or rollers 14 and 15 is thereafter ineffective to move the strips. In order to start the strips and move the perforated portion beyond the range of the feed rollers, it is necessary to press a key or lever 21 that is fast upon the transverse rock shaft 22, which latter carries, at its opposite end, an arm 23, the function of which latter will presently appear. Extending from side wall to side wall of the register is a second rock shaft 24 which, at its end adjacent the arm 23, is provided with a pawl 25 that projects across the extended end of a shaft 26 that is slidably mounted within the hollow main shaft 13, so that it may be moved or shifted longitudinally therein. At its intermediate portion the shaft 26 is connected to a conical clutch member 27 slidably mounted upon the shaft 13. The clutch member 27, with the inner shaft 26, is urged to the left (Figure 2) by an expansion spring 29, and when the key 21 is depressed to permit the shaft 26 to move to the left, clutch member 27 engages with an annulus or feed roller 30 loosely mounted upon the shaft 13 and having an inner conical surface for receiving the clutch member 27. When the annulus 30 is centered by the clutch member 27 it abuts against a block or stop 30^a on shaft 26 and said annulus is lifted into engagement with the strip and causes the periphery of the annulus to coat with the upper feed roller 16 so that a rotation of the crank 18 or a drive from the motor (to be hereinafter described) will cause a feeding of the strips a sufficient distance to carry the perforations therein out of the range of

the grooved feed rollers 14 and 15, so that the latter will again become effective for continuing the feed of the strip or strips until the next set of perforations are brought into registry therewith. The clutch member 27 is automatically disengaged from the annulus after a sufficient movement thereof, due to the end of shaft 26 having a threaded engagement with a threaded recess 31 in the under side of the arm 25 when the latter is in its upper position and resting upon the end of the shaft. Because of this threaded engagement between shaft 26 and the arm 25, this inner shaft travels to the right (Figure 6) at the beginning of its rotation thus moving the clutch member 27 out of engagement with the annulus 30, permitting the latter to drop back to its original loose position upon its shaft. The arm 25, fast on rock shaft 24, is pulled downwardly by a contraction spring 32 so that when the threads clear the recess 31 said arm will position itself in front of the threaded end of the shaft 26, and the side of the arm will then serve to hold the shaft 26 in its retracted position and consequently the clutch and annulus disengaged. A lateral finger 33 fixed to the rock shaft 24 is engaged by the upward movement of the arm 23 when shaft 22 is rocked by the depression of the key so as to lift the arm 25 sufficiently to permit the shaft 26 to be projected below said arm.

When it is desired to actuate the register by means of a motor, the handle or crank 18 is preferably withdrawn from its holder on the end of the roller shaft and the mechanism now to be described is employed for actuating the feed rollers.

A motor 34 having a motor shaft 35 is mounted in a suitable saddle or seat 36 secured to the side wall of the register opposite the crank 18 and starting key 21. The motor shaft carries the worm 37 that meshes with and drives a worm wheel 38 having an elongated hub or sleeve 40 mounted upon a stub 39 projecting from the side wall 10 and has its inner end up-set so that it will provide a retaining flange 41. This stub shaft near the wall 10 carries a loose gear 42 in mesh with a gear 43 on the feed roller shaft and connects with worm wheel sleeve 40 by the clutch elements 100 so that the motor will drive shaft 13 to feed the strips between its grooved rollers 14 and 15 and the upper friction roller 16 in the same manner as when the strips are fed by the manually actuated handle or crank 18.

The circuit wires or conductors 44 and 45 leading to the motor 34 have interposed therein a suitable switch so that the circuit may be opened when the register is being operated manually. This switch comprises a short arm 46 connected by a suitable binding post 47 to an insulating block 48 secured

to the side wall 10 of the register, as shown in detail in Figures 7, 8 and 9. A longer arm 50 is mounted between the insulating blocks 48 and 49 by a binding post 51 to which the conductor wire 45 is connected. These arms 46 and 50 carry, respectively, the contact elements 52 and 53, and the longer arm 50 is preferably yielding and at its upper end is provided with a lateral member 54 that has an insulating plate 55 upon its outer end. The longer arm 50, is of a yielding character so that it is normally urged toward the shorter arm whereby the contact elements 52 and 53 are in engagement with each other and the circuit is made or closed to the motor, and the latter will be operative. When it is desired to operate the structure by the handle crank, the yielding arm 50 is moved away from the outer arm 20 by means of a cam in the form of a wedge block 56 carried upon the adjacent side of a reciprocal link 57 that is connected at one end to a control lever 58, which latter is pivoted at its upper end upon a screw 59 threaded in wall 10 of the register. The opposite end of the link 57 is provided with an elongated slot 60 to receive a headed pin or bolt 61 projecting from the side wall of the register so that when said link is reciprocated by the control lever 58 the slotted portion will ride on the pin and the wedge block or cam 56 will engage and move the yielding arm 50 away from the shorter arm and thereby break the circuit so that the motor can not be operated although the feeding mechanism may then be controlled by the handle or crank 18.

When the feeding mechanism is actuated by the motor, the grooved rollers 14 and 15, when they come into registry with the perforation in the strip, will, of course, stop the feed of the latter, and unless some means are employed to control the motor the latter will continue to operate and the expense of running the motor would become quite an item. In this connection I have designed an automatic cut-out for the motor circuit so that after the same has operated a sufficient time to feed the complete ticket by means of the feed mechanism the circuit will be automatically broken and the motor stopped. This mechanism is controlled through the medium of the actuating key 21 which is employed to set the clutch mechanism for the initial feed of the strip. This control mechanism preferably comprises a cam device that is operated by hub sleeve 40 hereinafter referred to. This cam device may be of any suitable construction, and I have shown it as comprising a threaded sleeve 62 reciprocably mounted upon the hub sleeve 40 and guided by means of a lug 63 projecting into its bore and seated in an elongated groove or channel 64 extended longitudinally in said hub sleeve 40, which permits said

cam sleeve to be rotated with, but be moved longitudinally on the hub sleeve 40. This cam sleeve is urged toward the outer end of the hub sleeve 40 by a coiled expansion spring 65 that is interposed between one end 70 thereof and the gear 42, and said sleeve is provided, on its end nearest the register side wall with an annular flange 66 that is of greater diameter than the threads so that it projects beyond said threads. When sleeve 75 is reciprocated longitudinally upon the hub sleeve 40 the flange will engage the insulating plate 55 upon the adjacent end of the elongated yielding arm 50 of the switch heretofore described. The operation of this 80 cam or threaded sleeve is controlled by an L-shaped pawl 67, the downwardly extended end 68 thereof being so positioned that it engages the threads of the sleeve 62. The opposite end of this pawl 67 is secured fast 85 upon the rock shaft 24 that carries the arm 25 and is normally urged downwardly by the action of spring 32 that connected to the arm 25. When the shaft 24 is rocked by the depression of the key 21 the lateral finger 33 will be raised by the arm 23 as seen in Figure 5, and the L-shaped pawl 67 is lifted clear of the threads on the cam sleeve 62 while the latter, through the action of the spring 65 will be moved outwardly on the 90 hub sleeve 40 until the lateral member 68 of the L-shaped pawl will be engaged with the disk or annular flange 66, stopping further longitudinal movement of the cam sleeve and thereby releasing the elongated yielding arm 50 of the switch structure so that the circuit is closed to the motor and the latter begins to operate. The end of arm 23 at the end of its upward movement momentarily holds block 55 on the yielding switch 95 arm out of engagement with the flange 66 so as to avoid starting the motor before the arm 67 has engaged the threads 62. Upon releasing key 21 a slight reverse rocking of shaft 24 takes place when the arm 67 finds threads 62 which moves arm 23 downward far enough to clear the block 55 and the contact is made to form the circuit to the motor. This prevents removal of more than one set 100 of tickets at each depression of the starter key 21. The relative positions of these parts at the beginning of the operation of the motor is illustrated schematically in Figure 8 of the drawing. When the motor operates it drives the feeding mechanism through gear 42 and the strip is fed through the register in the manner heretofore described until the perforations come into registry with the grooved feed rollers 14 and 15 at which time the further movement of the strip is 105 stopped. The motor, however, will thereafter continue to run while the threads of the cam sleeve are rotating in engagement with the lateral member 68 of the L-shaped pawl. This moves the sleeve longitudinally 110

115

120

125

130

back upon the hub sleeve towards the in- it understood that all such changes and regulating plate 55 of the yielding switch finements are fully contemplated as coming arm 50, but when said parts come into en- within the scope of my invention as ex- gagement the disk or flange 66 will move the expressed in the appended claims.

- 5 switch arm 50 laterally and break the circuit. What I claim is:— 70
- so that the motor will be stopped. The lateral member 68 of the L-shaped pawl will maintain the parts in this position (Figure 7) until the key 21 is again depressed to reset the starting and feeding mechanism, operatively connected thereto, a cam rotated 75 which of course lifts the pawl 67 clear of the threads of the cam sleeve 62 and permits said sleeve to slide outwardly until the flange 66 comes into engagement with the lateral member 68 of the pawl to again close the switch. It will be understood that by strip moving means, 80 adjusting or regulating the amount of rotative movement of the threaded cam sleeve, the strip, mechanism for intermittently actuating the hub sleeve 40 the exact time for stopping the motor may be readily controlled, and it will also be understood that, operatively connected thereto; a cam moving when the structure is operated by the motor, will center the starter roller or elements 27 will cause the said longitudinal annulus 30 so that the strip will be fed a distance to move the perforations out of registry with the grooved rollers 14 and 15, 90 in the same manner as when the device is manually operated by the crank 18. This initial or starting movement is required both by the motor and by the hand operated mechanism, and when the feeding mechanism is to be actuated by hand the control lever 58 is moved to the position shown in Figure 9 with the contacts 52 and 53 out of engagement and the circuit broken. Gear 42 is normally urged towards the end of hub sleeve 40 to clutch therewith by an elongated spring plate 101 that is secured at its lower end to the register wall by a screw or rivet 102 and at its outer end is slightly enlarged and has an aperture 103 through which stub shaft 39 is passed. Intermediate its ends this spring plate is apertured for the passage of the screw 59 on which the lever arm 58 is pivoted, and surrounding the aperture is a tubular embossment 104 that engages the adjacent end of an enlargement on the pivoted end of lever arm 58. The contacting ends of these members have cam or oblique faces 105 so that when the lever arm is moved to open the switch the cam faces will move the spring plate 101 towards the register wall which allows the coil spring 65 to move the gear 42 away from the end of the hub sleeve 40 and disconnect the clutch members 100 so that the machine may be actuated by hand and all connection with the motor will be out of operation. 100
- 60 While I have herein illustrated and described a single specific embodiment of my invention, it is obvious that numerous changes and modifications may be made without departing from the principles I have herein disclosed. I therefore desire 105
1. In a strip feeding mechanism for auto-graphic registers, means for moving the strip, mechanism for intermittently actuating said means and including a driven shaft 110 operatively connected thereto, a cam mounted upon said driven shaft to be reciprocated thereby and rotated thereby, and devices for reciprocating said cam upon said shaft whereby to render the latter operative and inoperative with respect to said strip moving means. 115
2. In a strip feeding mechanism for auto-graphic registers, means for moving the strip, mechanism for intermittently actuating said means and including a driven shaft 120 operatively connected thereto; a cam mov- 125 ing said means and including a driven shaft operatively thereto, a cam mounted upon said driven shaft to be reciprocated thereby and devices for reciprocating said cam upon said shaft whereby to render the latter operative and inoperative with respect to said strip moving means. 130
3. In a strip feeding mechanism for auto-graphic registers, means for moving the strip, mechanism for intermittently actuating said means and including a driven shaft 135 operatively connected thereto, a cam mounted upon said driven shaft to be reciprocated thereby and rotated thereby, and devices for reciprocating said cam upon said shaft whereby to render the latter operative and inoperative with respect to said strip moving means. 140
4. In a strip feeding mechanism for auto-graphic registers, means for moving the strip, mechanism for intermittently actuating said means and including a driven shaft 145 operatively connected thereto, a threaded sleeve mounted to reciprocate upon said driven shaft and be rotated thereby and devices including an element adapted to engage the threads of said sleeve whereby during rotation said sleeve is reciprocated upon said shaft to render the latter operative and inoperative with respect to said strip moving means. 150
5. In a strip feeding mechanism for auto-graphic registers, a rotatable feed shaft, means on said shaft for moving the strip, a driven shaft, gears operatively connecting said feed shaft to said shaft, a cam rotated by said driven shaft, and devices for moving said cam from one position to another whereby to render said driven shaft operative and inoperative with respect to said feed shaft. 155
6. In a strip feeding mechanism for auto-graphic registers, a rotatable feed shaft, means on said shaft for moving the strip, a driven shaft, gears operatively connecting said feed shaft to said driven shaft, a cam mounted upon said driven shaft so as to be 160

reciprocated thereon and rotated thereby, and devices for reciprocating said cam upon said driven shaft whereby to render the latter operative and inoperative with respect to 5 said feed shaft.

7. In a strip feeding mechanism for automatic graphic registers, a rotatable feed shaft, means on said strip for moving the strip, a driven shaft, gears operatively connecting 10 said feed shaft to said driven shaft, a threaded sleeve mounted to reciprocate upon said

driven shaft and to be rotated when the latter is rotated, and devices including an element adapted to engage the threads of said sleeve whereby during rotation said sleeve is 15 reciprocated on said shaft to render the latter operative and inoperative with respect to the strip moving means.

Signed at Chicago, county of Cook and State of Illinois, this 27th day of March 20 1924.

LOUIS JENSEN.
